PLACER MINING MACHINE

James F. Noel, Rawlins, Wyo.

Application September 28, 1936, Serial No. 103,021

9 Claims. (Cl. 209—44)

This invention relates to placer machines, and the primary purpose of the invention is to meet the demand for a placer mining machine of simple construction, employing a minimum number of parts, especially bearing surfaces, and one that is rugged, durable, portable and which may be manufactured at a relatively low cost.

With the foregoing object outlined and with other objects in view which will appear as the description proceeds, the invention consists in the novel features hereinafter described in detail, illustrated in the accompanying drawings, and more particularly pointed out in the appended claims.

In the drawings,

Fig. 1 is a top plan view of the machine, partly broken away to facilitate illustration.

Fig. 2 is a side elevation.

Fig. 3 is an end elevation.

Fig. 4 is a longitudinal sectional view of the sluice box and screen, taken on the line 4—4 of Fig. 1.

Fig. 5 is a transverse vertical sectional view of the same, taken on the line 5—5 of Fig. 1.

Fig. 6 is a transverse vertical sectional view of a detail of the sluice box.

Fig. 7 is a longitudinal vertical sectional view of the same detail.

Fig. 8 is a transverse vertical sectional view of a detail of a modification.

Fig. 9 is a longitudinal vertical sectional view of the same.

Referring to the drawings, 10 designates a stationary frame, preferably formed of a pair of transverse channel irons 11 secured to and supporting a longitudinal channel iron 12.

A prime mover 13, such as an internal combustion engine is securely mounted on the frame at one end thereof. A horizontal transverse shaft 14 is rotatably mounted in bearings 15 arranged on the medial portion of the frame. Any suitable means may be employed for driving the shaft from the engine. For example, a belt 16 driven by a pulley 17 on the engine shaft may drive a pulley 18 fixed to the shaft 14.

Another frame 19 is supported on the main frame by vertically disposed leaf springs 20 which have their ends fixedly connected to the two frames, and the frame 19 is vibrated by means of a leaf spring pitman 21 having one of its ends encircling and driven by an eccentric 22 on the shaft 14. The other end of the pitman is secured to the frame 19 by any suitable means such as screws 23.

The sluice box 24 is removably mounted on

the frame 19, and as best shown in Fig. 5, riffles 26 are secured to the bottom of the box. Each riffle preferably consists of an angle iron extending longitudinally of the box and having its horizontal wing secured to the bottom of the box. The vertical wings of the angle irons divide the box into a series of longitudinally arranged parallel channels 27, and each channel contains undulated means 28 extending lengthwise thereof. Such means preferably consists of strips mounted on the horizontal wings of the angle irons and having undulated top surfaces. If two strips are employed in each channel, they can be arranged with their ridges 29 coinciding as shown in Figs. 6 and 7, or the ridges of the two strips may alternate as shown at 30 in Figs. 8 and 9.

The undulated strips form a novel system of inclined surfaces between the riffles which, due to a wedging action, prevent the material from becoming packed. The angle of the inclined surfaces and the rapidity and amplitude of the motion are determined by the character of the material treated, and the undulated strips act to keep the material in a loose condition, and this allows the heavy material, such as gold, to easily work its way to the bottom or to the spaces between adjacent angle irons. These spaces are occupied by toothed strips 31 which extend lengthwise of the box. Each tooth of these strips is preferably made up of vertical surfaces 32 from which inclined surfaces 33 slope downwardly toward the vertical surface of preceding teeth. As the heavy material enters the notches between the teeth, and the box reciprocates longitudinally, the concentrate is raised by the inclined surfaces 33 and is then pushed toward the outlet 34 by the vertical surfaces 32. Thus, a gradual delivery of concentrate is provided for, and it is unnecessary to make frequent clean-ups. The rate of delivery of the concentrate is determined by the size and angle of the surfaces of the toothed strips 31, the size of the opening in the spout 34, the motion and the distance the material has to be lifted.

Immediately above the sluice box, I arrange a screen 35 preferably of wire netting, and this screen has a wall 36 at three sides thereof, so that particles placed on the screen and too large to pass therethrough may be discharged by means of the outlet 37 at one side of the box. Material passing through the screen falls on to an imperforate sheet metal plate 38 which is preferably connected to the frame 35 of the screen and inclines toward one side of the box so that material deposited on the plate can be fed through an

opening 39 from the plate into the sluice box. Material which travels across the sluice box from the opening 39 to the opposite side of the box is delivered through an outlet 40.

5 By making the plate 38, the screen 35 and its frame removable from the sluice box, the whole top of the box may be uncovered to permit access to the interior of the latter.

In operation, the substantially liquid mixture 10 of materials containing the metal to be concentrated is deposited on the screen, and due to vibrations caused by the rotation of the shaft 14, some of this material will pass through the screen and land on the plate 38 which will direct it toward the opening 39. Large particles incapable 15 of passing through the screen will be discharged at one side of the machine through the outlet 37. The material flowing through the outlet 39 will first be acted upon by the riffle at one side of the 20 box, and then lighter materials will flow successively over the riffles until discharged through the outlet 40. Between the riffles, the lighter materials will be loosened and raised by the undulated strips 28, while the heavier metal will pass 25 into the spaces or notches between the teeth of the strips 31, and will be fed lengthwise of the sluice box until it reaches the outlet spout 34. It will be fed up and out of this spout by continuations of the toothed strips 31 which extend upwardly along the spout as illustrated in Fig. 4.

30 While I have disclosed what I now consider to be a preferred embodiment of my invention in such manner that the same may be readily understood by those skilled in the art, I am aware 35 that changes may be made in the details disclosed without departing from the spirit of the invention, as expressed in the claims.

What I claim and desire to secure by Letters Patent is:

40 1. A placer mining machine comprising a sluice box provided with a series of substantially parallel riffles which divide the bottom portion of the box into channels arranged side by side, means for introducing a liquid mixture of light materials and heavy materials into one of said channels, means extending lengthwise of the channels and having undulated top surfaces for raising the loose material and preventing it from packing in the channels, means for moving heavier materials lengthwise of the channels, and means for vibrating the box.

45 2. A placer mining machine comprising a sluice box provided with a series of substantially parallel riffles which divide the bottom portion of the box into channels arranged side by side, means for introducing a liquid mixture of light materials and heavy materials into one of said channels, strips extending lengthwise of the channels and having undulated top surfaces for raising the 50 loose material and preventing it from packing in the channels, means including toothed strips arranged in the channels between the riffles and strips for moving heavier materials lengthwise of the channels, and means for vibrating the box.

55 3. A placer mining machine comprising a sluice box, means for vibrating the sluice box, substantially parallel riffles arranged in the bottom portion of the box and dividing said portion into a series of channels arranged side by side, means 60 for depositing a liquid mixture containing light materials and heavy materials into an outermost one of said channels, means for discharging light material from the opposite outermost one of said channels, strips extending lengthwise of the 65 channels and having undulated top surfaces

adapted to loosen and raise said light material to prevent the same from packing in the channels, and toothed strips positioned in the bottom portion of the channels for feeding heavier material lengthwise of the channels, each tooth of the 70 toothed strips having a substantially vertical surface and an inclined surface sloping downwardly from said vertical surface toward the vertical surface of a preceding tooth.

4. A placer mining machine comprising a sluice 10 box, means for vibrating the sluice box, substantially parallel riffles arranged in the bottom portion of the box and dividing said portion into a series of channels arranged side by side, means for depositing a liquid mixture containing light 15 materials and heavy materials into an outermost one of said channels, means for discharging light material from the opposite outermost one of said channels, strips extending lengthwise of the 20 channels and having undulated top surfaces adapted to loosen and raise said light material to prevent the same from packing in the channels, and toothed strips positioned in the bottom portion of the channels for feeding heavier material lengthwise of the channels, each tooth of the 25 toothed strips having a substantially vertical surface and an inclined surface sloping downwardly from said vertical surface toward the vertical surface of a preceding tooth, said strips having alternately arranged ridges.

30 5. A placer mining machine comprising a sluice box having an inlet at one side and an outlet at the opposite side, substantially vertical riffles in the bottom portion of the box between the inlet and the outlet, said riffles dividing the bottom portion of the box into substantially parallel channels extending lengthwise of the box, an outlet spout at one end of the box for discharging concentrated material from the channels, strips projecting upwardly from the bottom of the box and arranged in said channels, said strips having undulated top surfaces and means in said channels between the riffles and strips for feeding heavy material through said outlet spout.

35 6. A placer mining machine comprising a sluice box having an inlet at one side and an outlet at the opposite side, substantially vertical riffles in the bottom portion of the box between the inlet and the outlet, said riffles dividing the bottom portion of the box into substantially parallel channels extending lengthwise of the box, an outlet spout at one end of the box for discharging concentrated material from the channels, strips projecting upwardly from the bottom of the box and arranged in said channels, said strips having undulated top surfaces and means in said channels between the riffles and strips for feeding heavy material through said outlet spout, the strips being arranged in pairs in each channel.

40 7. A placer mining machine comprising a sluice box having an inlet at one side and an outlet at the opposite side, substantially vertical riffles in the bottom portion of the box between the inlet and the outlet, said riffles dividing the bottom portion of the box into substantially parallel channels extending lengthwise of the box, an outlet spout at one end of the box for discharging concentrated material from the channels, strips projecting upwardly from the bottom of the 45 box and arranged in said channels, said strips having undulated top surfaces and means in said channels between the riffles and strips for feeding heavy material through said outlet spout, the strips being arranged in pairs in each channel.

and the strips of each pair having alternately arranged ridges.

8. A placer mining machine comprising a sluice box, means for vibrating the box, means for introducing material to be treated into one side of the box, means for discharging light material from the opposite side of the box, substantially parallel riffles arranged in the bottom portion of the box between the inlet and the outlet, each 5 riffle consisting of an angle iron having a horizontal wing spaced from adjacent riffles, and an upstanding wing, the upstanding wings forming a series of channels extending lengthwise of the box, an outlet spout at one end of the box for discharging heavier material from the channels, 10 strips mounted on the horizontal wings of the riffles and extending lengthwise of said channels, said strips having undulated top surfaces and toothed strips on the bottom of the box positioned 15 between the riffles for feeding heavier material lengthwise of the channels and through said outlet spout.
9. A placer mining machine comprising a sluice

box, means for introducing material to be treated into one side of the box, means for discharging light material from the opposite side of the box, substantially parallel riffles arranged in the bottom portion of the box between the inlet and the outlet, each 5 riffle consisting of an angle iron having a horizontal wing spaced from adjacent riffles, and an upstanding wing, the upstanding wings forming a series of channels extending lengthwise of the 10 box, an outlet spout at one end of the box for discharging heavier material from the channels, strips mounted on the horizontal wings of the riffles and extending lengthwise of said channels, 15 said strips having undulated top surfaces, toothed strips on the bottom of the box positioned between the riffles for feeding heavier material lengthwise of the channels and through said outlet spout, a foraminous screen positioned above the sluice box, and means for guiding material passing through the screen into the inlet 20 of the sluice box.
